UNITED STATES PATENT OFFICE.

WINCESLAS CAMILLE RECHNIEWSKI, OF PARIS, FRANCE.

CORE FOR DYNAMO-ELECTRIC MACHINES.

SPECIFICATION forming part of Letters Patent No. 378,375, dated February 21, 1888.

Application filed December 8, 1887. Serial No. 257,347. (No model.) Patented in France January 3, 1887, No. 180,659.

To all whom it may concern:

Be it known that I, WINCESLAS CAMILLE RECHNIEWSKI, a citizen of Russia, residing at Paris, in the Department of the Seine, France, 5 have invented a new and useful Improvement in Dynamo-Electric Machines, (for which I have obtained French Patent No. 180,659, dated January 3, 1887,) of which the following is a specification.

10 This invention relates to dynamo-electric machines; and it consists in an improved method of constructing and combining the cores of the electro-magnets and armatures, as hereinafter explained.

15 It is well known that in the construction of dynamo-electric machines it is very advantageous to employ electro-magnets having a core of soft iron, and especially of soft iron that has been worked—that is to say, rolled or 20 drawn out to a considerable extent.

According to this invention the elements or plates of the inducing electro-magnets are or 25 may be stamped or cut out from the same sheets as are employed to make the core of the armature or induced part composed of sheet-iron disks or rings, and in constructing the machine these elements or plates of the electro-magnets are arranged side by side in the same way as the disks or rings forming the core 30 of the induced part. By these means electro-magnets are obtained presenting a very superior structure. Moreover, the plates or laminæ composing the cores can be insulated from one another in the same way as the disks 35 or rings of the armature or induced part, and the improved electro-magnets can be combined with toothed armatures, or armatures having parts projecting radially (outward or inward) at their periphery.

40 The advantages attending toothed armatures—that is to say, a powerful inducing or magnetic field with a small expenditure of electric energy in the field-magnets—can thus be obtained without producing in the pole-45 pieces the Foucault currents, which usually result from the passage of the teeth of the armature before the said pole-pieces.

In order that the said invention may be 50 fully understood, I shall now proceed more particularly to describe the same, and for that purpose shall refer to the several figures on

the annexed sheet of drawings, the same letters of reference indicating corresponding parts in all the figures. These drawings illustrate, by way of example, the application of 55 the improved system of construction to various types of dynamo-electric machines, Figures 1 to 5 being elevations of different types of machines, and Fig. 6 a cross-section on line 6 6 of the type shown in Fig. 2. 60

In each of the figures, A represents the field-magnets, composed of a number of plates stamped out from sheets of wrought-iron; a, the exciting-coils, and B the armature.

Fig. 1 of the accompanying drawings represents an elevation, partly in section, of a horseshoe-magnet combined with a Siemens drum-armature provided with radiating teeth. On referring to the drawings it will be seen that plates or laminæ forming one element or 70 plate for the armature and one for the electro-magnet can be cut from one rectangular sheet of iron. The electro-magnets are attached to the bed-plate at their bases. a are two exciting-coils, and b is the bed-plate. 75

Fig. 2 represents an electro-magnet of the same kind combined with a Gramme ring-armature, also provided with radial teeth. The electro-magnet is not secured in the same way as the magnet in Fig. 1, being attached to the 80 base-plate b by one of its legs only. In this arrangement only one exciting-coil a may be employed.

Fig. 3 illustrates a multipolar machine in which the electro-magnets are arranged internally relatively to the armature, the plates or laminæ being placed directly on the axis. 85

Fig. 4 shows the application of the improved system to the construction of a dynamo-electric machine in which the advantages of great 90 compactness and small weight are combined. This arrangement of the parts will be readily understood on referring to the drawings.

Fig. 5 illustrates the application of the system to multipolar machines running at slow 95 speeds.

In Fig. 6 the several laminæ composing the field-magnets A and armature B are shown in section, being separated by washers b, of insulating material, such as commonly employed 100 for the purpose.

Having now particularly described and as-

certained the nature of this invention and in what manner the same is to be performed, I declare that what I claim is—

In a dynamo-electric machine, the combination of a toothed armature with a field magnet or magnets formed of plates or laminæ stamped out from sheets of wrought-iron, said plates or laminæ being placed side by side and insulated from one another, substantially as described.

In testimony whereof I have signed this specification in the presence of two subscribing witnesses.

WINCESLAS CAMILLE RECHNIEWSKI.
